J. S. PEDEN,
HEEL FOR SHOES,
APPLICATION FILED MAY 31, 1918.

1,307,985.

Patented June 24, 1919.

WITNESS
John S. Peden

INVENTOR
Joseph S. Peden

UNITED STATES PATENT OFFICE.

JOSEPH S. PEDEN, OF NEW YORK, N. Y.

HEEL FOR SHOES.

1,307,985.

Specification of Letters Patent. Patented June 24, 1919.

Application filed May 31, 1918. Serial No. 237,508.

To all whom it may concern:

Be it known that I, JOSEPH S. PEDEN, a citizen of the United States, residing at New York city, county of New York, and

5 State of New York, have invented certain new and useful Improvements in Heels for Shoes, of which the following is a specification.

This invention relates to the heels of shoes 10 and cushions therefor, and has for its object to simplify the construction of shoe heels; to provide a suitable supporting frame, and an efficient rubber cushion therefor, and to provide means whereby the latter may be 15 removed from or inserted in said frame at will; to provide means whereby the supporting frame may be securely fastened to the sole of a shoe; and to combine with the supporting frame of the cushion an ice-creeper 20 structure which may be put into readiness for use by simply removing the rubber cushion, and which is raised to a non-use position by the insertion of the rubber cushion in said frame.

25 These and other objects of my invention are set forth in the following specification, and shown in the accompanying drawings in which:—

Figure 1 is a side elevational view, partly 30 in section, showing my invention applied to the heel portion of a shoe, the remainder of the shoe being broken away;

Fig. 2 is a bottom plan view of my supporting frame showing the rubber cushions 35 projecting therefrom;

Fig. 3 is a perspective view of the frame showing the cushion and plate being withdrawn from the frame;

Fig. 4 is a transverse sectional view of the 40 frame and cushion, taken on the line 4—4 of Fig. 1;

Fig. 5 is a plan view of the metal plate for the rubber cushion;

Fig. 6 is a front elevational view, partly in 45 section, showing a modified form of frame; and

Fig. 7 is a plan view of a rubber cushion, illustrating a modified form of construction.

By the use of my invention, I make it possible to entirely do away with the necessity 50 for using leather lifts for the heels of shoes.

In carrying my invention into practice I form a frame A of metal, or any other suitable material, forming it into the usual 55 contour of a shoe heel and of the desired height.

Upon the inner face of the frame A I form flanges or partition pieces A², A³, A⁴, extending entirely around the inside of said frame, the flange A² being adapted to be forced in between the sole F of the shoe, 60 and the upper F¹ thereof, the frame being further secured to said sole by prongs E formed on the partition piece A³, which engages the outer lower surface of the sole, the said prongs being turned into said sole 65 when the frame is in place on the shoe, as shown in Fig. 1, and before the rubber cushion is put on in place.

The lower edge of the frame A is formed into projecting teeth A⁷ which will act as 70 an ice-creeper when the rubber cushion is removed, as more fully explained herein-after.

I form my rubber cushion in two parts or members as follows: I form a flat disk-like 75 plate of rubber B, of a size to fit the interior of the frame A, and to cover the entire heel tread surface of the shoe, and mold integral therewith a plurality of projecting buttons B², which are adapted to form the 80 tread of the heel. As shown in Figs. 4 and 6, I form a circumferential recess B¹ between the plate B and the button B².

The other member of the rubber cushion is a supporting plate D, formed of metal 85 or other suitable material provided with openings D² through which the buttons B² pass, and with smaller openings D¹ through which may pass screws or nails to fasten the rubber cushion to the sole of the shoe. 90 The openings D² are formed somewhat smaller in diameter than the buttons B², so that in assembling these parts, the buttons are forced through the openings until the sides of the openings seat themselves in the 95 circumferential recesses B¹, which results in the plate and buttons being securely held together without danger of displacement.

The rubber cushion thus formed is slid into the interior of the frame A between 100 the partition A³ and the flange A⁴, which form a slideway adapted to receive and support said cushion elements, which are held in place therein by nails or screws passing through the openings D¹ into the sole of 105 the shoe, an opening A¹⁰ being formed in the partition piece A³ to permit of the passage of the nails or screws therethrough.

In Fig. 6 I show a modified form of construction, in which the metal plate D is 110

extended and bent around upon itself to form a frame A¹, with an inwardly projecting flange A⁵, for engagement with the sole and the upper of the shoe as hereinbefore described, a space A⁸, being formed to receive said sole. In this form the partition piece A³ is omitted, the nails or screws passing through the plate D and rubber cushion B directly into the sole.

10 In Fig. 7 I show a large button at the rear end of the heel, and two smaller buttons at the front end thereof.

What I claim as new and desire to secure by Letters Patent is as follows:—

15 1. A heel for shoes comprising a frame having a top flange to support said frame upon the sole of a shoe, a partition piece within said frame having prongs for engagement with said sole to secure said frame in place thereon, a flange below said partition piece forming with the latter a slideway and support, and a rubber cushion supported within said slideway.

20 2. A heel for shoes comprising a frame having a top flange adapted to rigidly engage the sole of a shoe, a partition piece having prongs formed therewith for engagement with said sole to secure said frame thereto, a flange formed below said parti-

tion piece, and a cushion element consisting of a metal plate having rubber buttons projecting therefrom, secured between said partition piece and the last-named flange.

3. A heel for shoes comprising a frame adapted for attachment to the sole of a shoe, supplemental means of attachment thereto, a slideway formed within said frame, a cushion element consisting of a perforated plate having rubber buttons projecting therethrough supported within said slideway, and means for holding said elements in said slideway.

4. A rubber tread cushion for the heels of shoes comprising a flat approximately disk-like plate of rubber, buttons formed integral therewith having a circumferential recess adjacent to said plate, and a supporting plate having openings therein of a less diameter than that of said buttons, and the walls of which, when the buttons are forced therethrough, are adapted to seat themselves in said recess, and means for attaching said plate and rubber to a shoe.

In testimony whereof I, JOSEPH S. PEDEN, have signed my name to this specification this 28th day of May, 1918.

JOSEPH S. PEDEN.
